CLAIM

(57) The ornamental design for a covered filter basket, as shown and described.

DESCRIPTION

FIG. 1 is a top perspective view of a covered filter basket showing my new design;

FIG. 2 is a bottom perspective thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded top perspective view thereof; and,

FIG. 10 is a bottom perspective view of the cover portion of the covered filter basket with the filter basket removed for ease of illustration.
